UNITED STATES PATENT OFFICE.

LUDWIG PRZEDECKI, OF BRESLAU, GERMANY.

STRAW BAND FOR THE MANUFACTURE OF CIGARETTE MOUTHPIECES.

Application filed November 18, 1924, Serial No. 749,725, and in Germany October 8, 1924.

This invention has for its object a straw-band for the manufacture of cigarette mouthpieces and other articles in the straw industries, this straw-band consisting of a band of tissue paper, linen or any other suitable material and length, and of slit-up and flat-spread-out straw tubes attached to the tissue paper band in the manner herein-after described. My improved straw-band is distinguished from other known bands made of paper and formed into tubes, or from known straw-bands in which the slit and spread out straw tubes glued on the strip of tissue paper or other material have been utilized as cigarette mouthpieces, in that its manufacture is considerably simplified and cheapened thereby, that for the making of the finished band subsequently rolled on a spool, reel or the like, the slit and flat-spread straw tubes are directly glued lengthwise and in parallel rows upon a base-band of tissue-paper, linen or other suitable material, the fibres running in the direction of the said band. The width of the latter may be equal to that of bands for cigarette making machines usually used, or it may be or is made several or even a great many times that width. In the latter case it is then necessary by means of a suitable cutting machine to cut the rolled-up band into the correspondingly small bands.

A feature of novelty in my invention, as compared with known straw-bands wherein the ends of the slit and flat-spread straw tubes are caused to overlap and are glued together, is that the armour-like skin of the straw tubes at the places to be glued is removed, for instance by means of grinding tools, whereby not only a rough face for the sticking on of the glue is provided, but also a reduction of the thickness of the glued joint obtained. The straw tubes may either be treated singly in the manner described, or they are arranged in rows on wide tissue-paper bands or linen strips in the form of straw plates.

In the accompanying drawings:

Fig. 1 shows diagrammatically a small portion of the length of a base-band and straw tubes thereon of a width several times that of the band usual in cigarette making machines.

Fig. 2 shows also diagrammatically a short length of a modified form of the tissue-paper base-band with the slit-up and spread-out

straw tubes, this band being of the usual width;

Fig. 3 shows diagrammatically a third modification of the arrangement of the slit-up and spread-out straw tubes on the base-band;

Fig. 4 is a longitudinal section, on an enlarged scale, through the joint of two in the same line lying, slit-up and spread-out straw tubes according to the form shown in Fig. 2, and

Figs. 5 and 6 are cross sections through the lines A—B and C—D in Figs. 1 and 2 respectively, the bands being shown in perspective.

Referring to Figs. 1 and 5, there are gummed on the endless base-band 1 of tissue-paper, linen or any suitable material of any desired length and a width several times that of the base-band usually used in a cigarette making machine, a series of slit and flat spread-out straw tubes with the fibres thereof running longitudinally in the direction of the aforesaid band, in such a manner, that longitudinally disposed rows $a^1, a^2, a^3 \dots, b^1, b^2, b^3 \dots$ of the straw tubes are formed of which the joints lie flush in a line and below each other. Subsequent to the winding or rolling upon a spool or roller of any suitable size of the thus gummed straw-band, the latter is cut through by a cutting device on the lines I—I, II—II and III—III, and in this way divided into the separate smaller bands. These bands, in turn, are then cut in strips of any suitable length and made to form mouthpieces for cigarettes of the required size.

According to the modification, Figs. 2 and 6, I provide a base-band 1^a which corresponds with the width of the band commonly known in cigarette making machines. The slit and flat spread-out straw tubes $a^1, a^2, \dots, b^1, b^2, \dots, c^1, c^2, \dots$, however, are in this case and preferably in all forms ground at their joining ends and reduced as shown in Fig. 4 on a large scale, the slit and spread-out straw tube a^1 , by means of known grinding tools, being ground on the armour-like upper face and the other straw tube a^2 on the also armour-like underface. The joints of the flattened straw tubes are therefore forming an even surface with the other parts thereof and consequently allow of an easy and smooth winding up on a spool or roller of the straw-band.

According to the modification, Fig. 3, there is again provision made of a base-band 1^b of a width several times that of a usual band, the novel feature in this modification being that the straw tubes are so placed that the joints *x* of one of the straw tube rows are set off against those *y* of the neighboring straw tube. It will be understood that also a band, such as shown in Fig. 2, may have 10 the straw tubes gummed and arranged in the same way as described with reference to Fig. 3.

For the removal of the silicic acid cover a grinding-wheel may be employed, the axle 15 thereof being mounted parallel to the fibres of the straw tubes. The latter or the joined straw tube plates are hereby moved under the grinding-wheel and laterally of the direction of the straw fibres, or, the said grinding wheel may be moved along the ends of 20 the straw tube or plate and laterally of the fibres. In place of the joining of the straw tubes by glue, they may also be connected by surface attachment, for instance by causing 25 the straw tubes to be drawn through the relief rollers known for such purposes. It is also possible to combine both methods of connection.

This improved method is not only adapted 30 for the making of cigarette mouth-pieces, but it can also find use not only in the manufacture of straw hats and the whole of the straw-working industries. As tests have shown the bands at the connecting places of 35 the straw tubes have a great strength of extension and exceed in this respect the known bands in which the straw tubes or strips of a straw tube plate are connected at their ends by gumming lashes.

40 What I claim as new and desire to secure by Letters Patent is:—

1. A strawband comprising a base of sheet material bearing upon one of its surfaces a

row of flattened straw strips arranged in parallel relation with their longitudinal 45 edges abutting, said strips having roughened bottom faces formed by the removal of the natural hard skin coating thereof, whereby thinned strips of increased flexibility are produced, said roughened faces of the strips 50 being cemented to the said base of sheet material.

2. A strawband comprising a base of sheet material bearing upon one of its surfaces a plurality of transverse rows of flattened 55 straw strips, the strips of each row having their longitudinal edges abutting and the strips of the several rows being disposed in longitudinal alinement and having their end edges abutting, said strips having roughened bottom faces formed by the removal of the natural hard skin thereof, whereby thinned strips of increased flexibility are produced, said roughened faces of the strips 60 being cemented to the said base of sheet 65 material.

3. A strawband comprising a base of sheet material bearing upon one of its surfaces a plurality of rows of flattened straw strips, the strips of each row having their ends 70 reduced and overlapping within the thickness of a strip, and the strips of the several rows being disposed in parallel relation with their longitudinal edges abutting, the abutting ends of the strips of each row being arranged between and in break-joint order 75 with the abutting ends of the strips of an adjacent row or rows, the said strips of the rows being reduced to less than normal thickness by removal of the hard natural 80 skin from the bottom surfaces thereof, leaving said surfaces roughened, said roughened surfaces being cemented to the sheet of base material.

LUDWIG PRZEDECKI.
